UNITED STATES PATENT OFFICE.

ZACHARY T. BROWN, OF THOMPSON, PENNSYLVANIA.

STAMP-AFFIXER.

No. 890,330.

Specification of Letters Patent.

Patented June 9, 1908.

Application filed December 21, 1907. Serial No. 407,516.

To all whom it may concern:

Be it known that I, ZACHARY T. BROWN, citizen of the United States, residing at Thompson, in the county of Susquehanna and State of Pennsylvania, have invented 5 certain new and useful Improvements in Stamp-Affixers, of which the following is a specification.

This invention is a machine for affixing 10 postage stamps to letters or other mail matter, and more particularly a machine of this kind in which the stamps are arranged in a band or ribbon and wound on a drum from which they are unwound as needed, and 15 moistened, severed and affixed.

The invention has for its object to provide 20 a machine of this kind which is simple in construction and reliable in operation; and a further object is to provide a register which 25 is operated by the severing and affixing device.

In the accompanying drawing, Figure 1 is 30 a side elevation of the invention. Fig. 2 is a top plan view. Fig. 3 is an enlarged end 25 view, and Fig. 4 is a section on the line 4—4 of Fig. 3.

Referring specifically to the drawings, a 35 suitable frame having side walls 5 and 6, respectively, is provided on which the working parts are supported. The side walls are preferably in skeleton form, as shown, for the sake of lightness. At one end of the frame are bearings for the axle 7 of a horizontally disposed drum 8 the rim of which is divided 40 into two sections 9 and 10, respectively, by means of an annular plate 11. The postage stamps are arranged in a band or ribbon 12 and fastened at one end to and wound on the section 9, and a band 13 for a purpose to be 45 hereinafter described is fastened at one end to and wound on the section 10.

On the axle 7 is a pinion 14 which meshes 50 with a spur-gear 15 mounted in suitable bearings on the supporting frame of the machine, 45 and fitted with a handle 16 for turning it. Through this gearing the drum is rotated to wind the bands 12 and 13 thereon.

In front of the drum are horizontally disposed rollers 17 and 18, respectively, which 55 are arranged one above the other and extend transversely across the frame. Adjustable bearing boxes 18^a are provided for the axle of the roller 17 in order that it may set closer to or farther away from the roller 18.

55 In front of the rollers 17 and 18 is a moistening roller 19 which is mounted in a trough

20 containing water. The trough extends between and is secured to the side walls 5 and 6 of the frame. In front of the moistening roller is a cross-bar 21 which extends between the side-walls 5 and 6 and is for a purpose to be hereinafter described. The moistening roller is in alinement with the section 9 of the drum so that the stamp band 12 may pass thereover, and it does not extend 65 entirely across the frame, its length being slightly greater than the width of the stamp band.

On one side of the moistening roller, above the trough 20 is secured an elongated tube 22 through which the band 13 passes, the tube being in alinement with the section 10 of the drum. In this tube is a hole 23 for a purpose to be hereinafter described.

The rollers 17 and 18 are rotated through 75 the following gearing: On the axle of the roller 18 is a pinion 24 which meshes with a spur-gear 25 mounted in suitable bearings on the frame, and having a handle 26 for turning it. The rollers are set sufficiently close 80 together so that the roller 17 will rotate with the roller 18 when the bands 12 and 13 are therebetween. The moistening roller 19 is also driven by the spur-gear 25 through the following gearing: On the axle of said roller 85 25 is a pinion 27 which is geared to the pinion 24 by an intermediate pinion 28 so that the moistening roller may turn in the same direction as the roller 18.

In front of the moistening roller is a wall 90 29 having a slot 30 through which the stamp band 12 passes, and in front of the wall below the slot is a table 31 on which the mail matter to be stamped is placed.

In front of the wall 29 is a stamp severing 95 and affixing device. Said device comprises a lever 32 pivoted at 33 to an extension 34 on the side wall 6 of the frame, and having a handle 35. The lever works close to the wall, and is normally held elevated above the 100 slot 30 by a spring 36 connected at one end to the lever and at the other end to a standard 37 rising from the frame. One side of the lever is enlarged as indicated at 38 to the same dimension as the stamps so that the 105 latter may be pressed down thereby on the mail matter and thus affixed thereto.

Above the tube 22 is a recording device comprising a lever 39 pivoted to the side 5 of the frame and carrying at its free end a 110 punch point 40. The lever is held normally elevated by a spring 41 secured at its ends to

the lever and to the side 5, respectively. The hole 23 is so located that when the lever 39 is depressed the punch 40 enters the same and makes a hole in the band 13.

5 The punch is operated as follows: At the free end of the lever 39 is a projection 42 which is in the path of a projection 43 on the lever 32 so that when the latter is depressed to sever and affix a stamp, the lever 39 is 10 depressed to punch the bands 13. Said band after it leaves the tube 22 passes over the edge of the trough 20 and downwardly in the open space between the side walls of the frame in front of the table 31, and to its 15 free end is attached a weight 44 for taking up slack.

The machine operates as follows: The bands 12 and 13 are fastened at one end to the drum and wound thereon by turning the 20 spur-gear 15. The free ends of the bands are then passed between the rollers 17 and 18, and the band 12 is carried under the cross-bar 21, over the moistening roller 19, and through the slot 30. The band 13 is 25 passed through the tube 22 and the weight 44 is attached to its free end. To affix a stamp to a letter or other mail matter the rollers 17 and 18 are turned which feeds both bands forward. When the stamp projects far 30 enough from the front end of the slot 30, the lever 32 is depressed which severs the stamp with a shear cut along the line of perforations and a further depression of the lever affixes it to the letter by pressing it thereon. 35 At the same time the punch 40 is operated, as described, to punch a hole in the band 13. The last mentioned band is fed forwardly with the stamp band and punched every time a stamp is affixed so that an accurate 40 count of the number of stamps used is kept. The cross-bar 21 is slightly below the periphery of that portion of the moistening roller which is outside the trough 20 so that

the band will be held thereagainst. In front of the moistening roller is also a cross-bar 45 45 under which the stamp band passes and which holds it close to the roller. As the moistening roller also rotates it tends to feed the stamp band forward.

I claim:—

50 1. A stamp-affixer comprising a drum which is divided into two sections one of which receives a band of stamps, and the other a recording-band, a stamp severing and affixing-device, means for feeding the stamp band thereto, means for moistening stamps, and a punch operating on the recording-band and actuated by the severing and affixing-device.

2. A stamp-affixer comprising a drum 60 which is divided into two sections one of which receives a band of stamps and the other a recording-band, stamp moistening means, a stamp-severing and affixing-device, a pair of feed-rollers receiving said bands 65 therebetween, and a punch operating on the recording-band and actuated by the severing-device.

3. A stamp-affixer comprising a drum which is divided into two sections one of 70 which receives a band of stamps and the other a recording-band, stamp moistening means, a stamp-severing and affixing-device, means for feeding the stamp-band thereto, a tube through which the recording-band 75 passes and having a hole, and a punch operating on the recording-band through the hole in the tube, and actuated by the severing and affixing-device.

80 In testimony whereof I affix my signature, in presence of two witnesses.

ZACHARY T. BROWN.
